TELESCOPE MOUNTING FOR GUNS

Donald D. Demick and Joseph J. Bartolat,
Tacoma, Wash.; said Demick assignor to said
Bartolat

Application February 16, 1951, Serial No. 211,286

4 Claims. (Cl. 33—50)

1

The present invention relates to a telescope mounting for guns and it consists in the combinations, constructions and arrangements of parts herein described and claimed.

Generally the invention comprises the provision of an iron sight provided with windage and elevation adjustments and which iron sight forms a part of a telescope sight mounting of that type shown, for example, in the patents to Redfield, No. 1,837,290 of December 22, 1931, and Buehler, No. 2,486,002 of October 25, 1949. The iron sight forming the present invention may be adjusted for windage and elevation with respect to the gun upon which the same is mounted and, when once so adjusted, need not be further disturbed even when the telescope sight is mounted upon or removed from the telescopic sight mounting of which the present invention forms a part.

It is accordingly an object of the invention to provide a device of the character set forth which is simple in construction, inexpensive to manufacture and yet effective and efficient in use.

Another object of the invention is the provision of an iron sight forming a part of a conventional telescopic sight mounting.

A still further object of the invention is the provision of an iron sight forming a part of a telescopic sight mounting and having novel means for adjusting the elevation and windage positions thereof.

Other and further objects of the invention will become apparent from a reading of the following specification taken in conjunction with the drawing, in which:

Figure 1 is a side elevational view of an embodiment of the invention,

Figure 2 is a plan view thereof.

Figure 3 is an exploded perspective view of the elements forming the present invention,

Figure 4 is an enlarged sectional view taken along line 4—4 of Figure 2, and

Figure 5 is an enlarged sectional view taken along line 5—5 of Figure 1.

Referring more particularly to the drawing, there is shown therein a rifle 10 upon which a gun sight mount 11 is engaged for securely mounting thereon a telescopic sight (not shown). The presently described mount 11 is of that type shown in the Buehler patent above referred to but is not necessarily confined to that showing, it being understood that the present invention may be applied to other telescopic gun sight mountings of similar character.

The mount 11 is provided with a fixed base 14

2

having a front base section 15 and a rear base section 16 connected together by a side arm 17 which side arm or connecting bar 17 is formed as an extension of the front and rear sections on one side of the base 14. The front base section is provided with vertically extending openings for the reception of bolts 18 or the like and the rear base section 16 is provided with an opening for the reception of a bolt 19 or the like, such bolts 18 and 19 being adapted to maintain the base 14 in fixed position upon the rifle 10.

The front end of the base 14 is formed with a pair of forwardly extending clamping arms 20 and 21 which form an adjustable clamp 22 at this end of the base 14 within which a front telescopic sight-engaging ring (not shown) may be mounted, the arms 20 and 21 being formed with a peripheral opening 23 for this purpose. A set screw 24 engages through the outer ends of the arms 20 and 21.

The rear portion 16 of the base 11 is formed with a pair of notches or cut outs 25 on the opposite sides thereof. The notches 25 open through the upper and lower surfaces of the base 11 and are substantially annular for partially enclosing the round heads 26 of bolts engageable in the base section 16.

The bolts 27 are provided with annular heads 26 having an inner concave surface as shown at 28. Flanges 29 are thereby formed about the annular head 26 and the shank of the bolt 27 extends concentrically from the center of the head 26. The bolts on the opposite sides of the base portion 16 are oppositely threaded, that is, one of the bolts is threaded for left hand rotation and the other threaded for right hand rotation.

A rear telescopic sight-engaging ring (not shown) is adapted to be releasably engaged by the flanges 29 in the manner shown, for example, in the Buehler patent above referred to.

The windage adjustment for the telescopic sight is made by properly positioning the screws 27. After the proper adjustment is made for the telescopic sight, the left screw, as viewed in Figure 4 of the drawing, remains constantly in the position thus found and is never turned again, and the other of the two screws 27 is removed and replaced when the telescopic sight is removed from or replaced upon the rifle, it being understood that the mount 11 remains upon the rifle 10 at all times.

The device forming the present invention consists of a block 30 which is adapted to extend transversely across the rear base portion 16 and which is provided at either side with an arcuate

slot 31 into which may be engaged the flanges 29 to thereby hold the block fixedly in position atop the mount 11. The block 30 is centrally provided with a longitudinally extending depressed portion 32 and the rear face of the block 30 is provided with a recess 33 in which a flat sight plate 34 is vertically slidably, the shoulders 35 formed by the recess 33 in the block 30 acting as vertical guideways for the plate 34.

Adjacent the upper and outer corners of the recess 33 the block 30 is provided with threaded openings 36 and the plate 34 is provided with a vertically extending slot 37 adjacent each side thereof, the slots 37 being adapted to register with the openings 36 in the block 30.

A pair of screws 38 extend through the slots 37 and engage in the openings 36 by which means the plate may be held in various selected vertical positions upon the block 30. The plate 34 is centrally provided with a sight opening 39.

A threaded opening 40 extends angularly downwardly and outwardly from the depressed portion 32 of the block 30 to the lower end of one side of the block 30 and a windage screw 41 is threaded therein. The screw 41 is provided with a head 42 and a tapered nose 43 which is adapted to engage beneath the flange 29 of the screw 27 adjacent to its side of the block 30.

A threaded opening 44 extends inwardly from the front face of the block 30 and communicates with the threaded opening 40, as clearly shown in Figure 4, and a set screw 45 is threadably mounted in the opening 44.

In operation, it will be apparent that when the rings supporting the telescopic sight are removed from the mount 11, that the block 30 may be engaged by the flanges 29 entering the arcuate grooves 31 and that thereafter the proper windage setting for the block 30 and consequently the sight plate 34 may be had by manipulating the heads 26 of the screws 27 until a proper alignment is had between the sight opening 39 and the forward sight of the rifle. When this has been properly ascertained, the screw 41 may be threaded inwardly in the opening 40 until the tapered nose 43 engages beneath the concave surface 28 of the screw head 26 adjacent that side of the block 30. This action having taken place, the set screw 45 is threaded inwardly of the block 30 to thereby abut against the screw 41 to maintain the same fixedly in position in its opening 40. Thereafter, no further windage adjustment will ever be necessary for the block 30 or the plate 34 since it is only necessary to remove the right hand screw 27 as viewed in Figure 4 to release and replace the block 30 upon the mount 11.

To set the proper elevation for the plate 34 and its sight opening 39, it is only necessary to loosen the screws 38 and adjust the proper vertical position of the plate 34 thereafter tightening the screws 38 to maintain the plate 34 fixedly with respect to the block 30. Hence it will be seen that once the proper windage and elevation adjustments have been made for the device forming the present invention it will only now be necessary to insert the block 30 and its attached elements into engagement with the flanges 29, as aforesaid after the telescopic sight has been removed from the rifle 10 and without further adjustment being necessary. The present device furnishes an iron sight for a rifle equipped with a mount for telescopic sights, it being understood that ordinarily, when a telescopic sight mount is placed upon a rifle, the conventional rear sight

or iron sight becomes useless due to the fact that the mount itself is interposed in the line of sight between the conventional rear sight and the conventional front sight of the rifle.

While but one form of the invention has been shown and described herein, it will be readily apparent to those skilled in the art that many minor modifications may be made without departing from the spirit of the invention or the scope of the appended claims.

What is claimed is:

1. A device of the character described comprising, in combination, with a telescopic sight mount having a pair of inwardly directed oppositely mounted retaining screws each having heads provided with concave inner faces, the provision of an iron sight releasably engageable by said screws, said iron sight including a laterally extending block having an arcuate slot at each side thereof for the reception of the concave inner faces of said retaining screws and a vertically extending recess in the rear face of said block, a sight plate vertically slidably in said recess, means for locking said plate in selected vertical positions in said recess, said block having a central depressed portion in the top thereof and having a threaded opening extending downwardly and outwardly from said depressed portion, and a windage screw engaged in said threaded opening and having a tapered nose engageable with the concave inner face of the adjacent screw head.

2. A device of the character described comprising, in combination with a telescopic sight mount having a pair of inwardly directed oppositely mounted retaining screws each having heads provided with concave inner faces, the provision of an iron sight releasably engageable by said screws, said iron sight including a laterally extending block having an arcuate slot at each side thereof for the reception of the concave inner faces of said retaining screws and a vertically extending recess in the rear face of said block, a sight plate vertically slidable in said recess, means for locking said plate in selected vertical positions in said recess, said block having a central depressed portion in the top thereof and having a threaded opening extending downwardly and outwardly from said depressed portion, and a windage screw engaged in said threaded opening and having a tapered nose engageable with the concave inner face of the adjacent screw head, said means for locking the plate including a vertically extending slot adjacent each side of said plate, a lock screw extending through each of said slots and threadably engageable with said block.

3. A device of the character described comprising, in combination, with a telescopic sight mount having a pair of inwardly directed oppositely mounted retaining screws each having heads provided with concave inner faces, the provision of an iron sight releasably engageable by said screws, said iron sight including a laterally extending block having an arcuate slot at each side thereof for the reception of the concave inner faces of said retaining screws and a vertically extending recess in the rear face of said block, a sight plate vertically slidable in said recess, means for locking said plate in selected vertical positions in said recess, said block having a central depressed portion in the top thereof and having a threaded opening extending downwardly and outwardly from said depressed portion, a windage screw engaged in said threaded open-

ing and having a tapered nose engageable with the concave inner face of the adjacent screw head, and a set screw extending inwardly from the front side of said block and engageable with said windage screw whereby to lock the same in selected positions.

4. A device of the character described comprising, in combination with a telescopic sight mount having a pair of inwardly directed oppositely mounted retaining screws each having heads provided with concave inner faces, the provision of an iron sight releasably engageable by said screws, said iron sight including a laterally extending block having an arcuate slot at each side thereof for the reception of the concave inner faces of said retaining screws and a vertically extending recess in the rear face of said block, a sight plate vertically slidable in said recess, means for locking said plate in selected vertical positions in said recess, said block having a central depressed portion in the top thereof and having a threaded opening extending downwardly and outwardly from said depressed portion, a windage screw engaged in said threaded opening and having a tapered nose engageable with the

10
